(Cl. D15—1)

To all whom it may concern:

Be it known that I, Joseph V. Faust, a citizen of the United States, residing in the city of St. Louis, in the State of Missouri, have invented a new, original, and ornamental Design for Chairs, of which the following is a specification, reference being had to the accompanying drawing, forming part thereof.

In the drawings:

Fig. 1 is a perspective view of a chair showing my new design.

Fig. 2 is a front elevation of a chair showing my new design.

I claim:

The ornamental design for a chair, as shown.

JOSEPH V. FAUST.
